SWITCH

George E. Breeze, Saugus, Mass., assignor to The Palmer Electric & Manufacturing Co., Wakefield, Mass., a corporation of Massachusetts

Application November 2, 1948, Serial No. 57,905

14 Claims. (Cl. 200—16)

1

This invention relates to alternating current switches in which contacts meet each other axially along a shaft driven by a manually operable member, such as a hand-wheel, through a mechanism which causes the shaft to make and break the current without undue arcing, and without improper or undesired operation under the motion of the hand-wheel.

The following are some of the features of the invention which are believed to be new and important in the art, as contrasted with prior switches. The conventional sweep-contact type of rotary switch has the following weaknesses, (1) because of the uncontrolled speed of the moving contacts and the lack of sufficient maintained pressure, arcing occurs, (2) there is also considerable contact wear that reduces the efficiency of the device and increases heating, (3) the physical design of the insulating members of the arc-snuffing mechanism is inadequate, causing the switch to be short-lived under continual operation at its rated capacity, (4) in the conventional type rotary switch, there is no provision made to prevent instantaneous operation from an "on" position, through an "off" to another "on" position, which can be destructive in the case of multiple power sources of reversed phase or polarity, (5) the conventional type rotary switch is bulky because of its large gaps between contacts, (6) most rotary switch designs are such that the spring members carry current, resulting in the loss of spring properties due to heating occasioned by an overload, and (7) most rotary switches are actuated by a spring drive mechanism, so that if the spring drive fails, positive indexing of the contacts is difficult, if not impossible. Because of these weaknesses, the following features of my switch are believed to be novel and important.

For example, the following features of my switch are believed to be new and inventive, namely, (1) the idea of controlling the rate of contact separation, by means of a detent mechanism, in combination with a contact operating cam, so that a minimum of arcing occurs, because the current is permitted to break while the contacts are close enough together to effectively carry away the heat of the arc, and to partially exclude air, which would otherwise carry oxygen to help maintain the arc (this same mechanism tends to speed up the closing action of the contacts, thereby reducing the extent of arcing), (2) in my device, because of the linear and substantially non-sliding movement of the contacts, wear is reduced to a minimum, the contacts being moved by means of a cam-operated link which is

2

guided by a slot in the housing, (3) the arc chambers are so designed that they reduce the amount of air which may approach the arc and also effect an increase in the gas pressure at the contacts upon "breaking," thereby tending to blow out the arc, and effectively protect the switch from damage, and are easily replaceable, (4) a simple delay mechanism will permit normal operation from "on" to "off" position without stopping, but in a case of an attempt to move the hand-wheel too rapidly through this sequence, the mechanism will lock and cause a positive delay in the "off" position until turning pressure has been released from the hand-wheel, as by a follower, herein a ball associated with two springs and a ramp arranged to cause locking of the driver, (5) it is possible to break and to maintain a 450 volt circuit open with a contact spacing of only three-eighths of an inch (this is further enhanced by the fact the large contacts effectively fan out and carry away current and heat originating at the very small area of the contact surfaces actually touching each other, resulting in cooler contacts and current-carrying members), thus permitting the switch body itself to be smaller, and reducing weight and size of the overall device, (6) the contact springs are entirely divorced from the contacts themselves, and do not, therefore, carry current, thus ultimately reducing the heating, and increasing the life of the switch, and (7) the contact-operating cam and the position-indicating means (marks on the handwheel) are rigidly tied together by the shaft, and the contacts can be positively positioned, as desired, even though the detent mechanism fails or is completely removed from the device. Still other features will be pointed out during the course of the following description of one embodiment of the invention shown in the drawings, while its scope will be pointed out more particularly in the appended claims.

In the drawings:

Fig. 1 is a plan (an end view) of a switch embodying the invention;

Fig. 2 is a sectional view on line 2—2 of Fig. 1; Fig. 3 is a sectional view on line 3—3 of Fig. 2; Fig. 4 is a sectional view on line 4—4 of Fig. 3; Fig. 5 is a sectional view on line 5—5 of Fig. 2; Fig. 6 is a sectional view on line 6—6 of Fig. 2; Fig. 7 is a sectional view on line 7—7 of Fig. 2; Fig. 8 is a sectional view on line 8—8 of Fig. 2; Fig. 9 is a view partly in elevation and partly in section looking in the direction shown by the arrow 9 in Fig. 8; Fig. 9A is a development of the cam-track;

Fig. 10 is a sectional view on line 10—10 of Fig. 5;

Fig. 11 is a plan view of the "lower" contact member, and

Fig. 12 is an elevation of the "lower" contact member as viewed from the right-hand side of Fig. 11.

Referring to the drawings and to the embodiment of the invention illustrated therein as an example, there is shown a three-pole switch (see Fig. 1) comprising a hand-wheel or other handle 14, a panel indicator 16, a housing 18, comprising a top-plate 20, a bottom-plate 22 (see Fig. 2) connected by studs 24 and nuts 26 and surrounded by insulating sleeves 28. A shaft 30, affixed to the hand-wheel 14, extends through the top and bottom plates 20 and 22, which afford bearings for the shaft. This shaft is square (see Fig. 3) and has a corner which is chamfered at 32 to serve like a spline as a means to ensure proper assembly of the parts on the shaft. About the shaft, there is an insulating sleeve 34 (see Fig. 2) also square, to which are fitted certain parts hereinafter described.

In its simplest form, the switch may have but one set of upper and lower contacts or contact members, but actually there are three sets. For a proper understanding of the invention, for the present, but one set will be described. This set comprises an upper contact comprising a bridge 36 and a pair of projections 38A, 38B, all of copper. For convenience of manufacture, the projections are in the form of studs having shanks 40A, 40B, "staked" in place, and then soldered. For the sake of durability the studs are faced with disks 42A, 42B, comprising 50% silver and 50% tungsten, soldered in place with silver solder. Also, for best results, the disks have their contacting faces convex.

There are similar lower pairs of contacts, in this case, one a stud 44A having a shank 46 affixed to a bar 48A, and the other contact 44B, in this case formed on a bar 48B for convenience of manufacture. In this case, also, there are disks 50A, 50B, as before. The exact form of the bars 48A, 48B (see Fig. 8) will differ from each other according to the circumstances. In the case of the bar 48A, (see Fig. 11) for example, there are other contacts affixed thereto for cooperation with other upper contacts. In the case of the bar 48B (see Fig. 8), the form is simple, and there are no other studs attached thereto.

Returning now to Fig. 9, it will be observed that the upper and lower contacts are shielded and surrounded by bodies of insulating material, in this instance, thick disks 52 and 54 closely fitted about the contacts. Furthermore, there are sleeves 56A, 56B, to shield the confronting faces and the sides of the upper and the lower contacts. These sleeves are made of insulating material, for example, grey fiber tubing, which is found to be the best for the purpose, far better than others tried. These sleeves shield the ends of the contacts by limiting the air about them to a minimum amount. By these sleeves and these disks failures due to large overloads are avoided. The importance of this feature can hardly be overestimated.

The upper contact is moved up and down by mechanism including a link 58 affixed as by a stud 60 to the contact and having at its upper end a follower such as a roller 62 turning about a pin 64. The follower moves under control of a cam 66 having a track 68, the form of which will be hereinafter described. Thus, the cam, as

it turns, lifts and lowers the upper contact. The mechanism to turn the cam will be described presently. Referring to Figs. 7 and 8, in this instance, there are two other sets of upper and lower contacts generally similar to those just described, including two upper contacts 70 and 72 operated by links 74 and 76, similar to the link 58 and carrying like followers 78 and 80 in the track 68 of the cam 66, as before. In the case of the upper contact 70, the latter bridges lower contacts 82 and 84, one on the bar 48A and the other on a bar 86. In the case of the upper contact 72, the latter bridges lower contacts 88, 90, one on a bar 92 and the other on the bar 48A (see Fig. 11). This particular arrangement contemplates a triple-throw switch for certain purposes, indicated by markings "1," "2," and "3" on the hand-wheel 14 (see Fig. 1), and by markings "o" which are for open positions to correspond with the first-named markings. The hand-wheel 14 may be turned in either direction. There are also markings "Load," "1," "2," and "3" on the bars 48A, 48B, 86 and 92 (see Fig. 1).

The cam 66 is mounted on the sleeve 34 (see Fig. 6), and is housed within a housing 94, having slots 96, 97, and 98 for the links. The cam carries a set of springs 100 (see Fig. 2) whose upper ends rest against a pair of thrust washers 102 below a housing disk 104 of insulating material held by the tie-rods 24. Below the cam 66 there are similar thrust washers 106, seated in an annular groove 108 in the insulating disk 52, and the cam 66 has a depending portion to seat upon said washers. Thus, the cam is retained between upper and lower thrust washers which limit backlash, and with the springs, transmit the motion of the cam to the movable contacts, applying pressure in the "closed" position of the contacts. The cam has, at its upper end, an annular groove 110 in which there is a split ring 112 seated to complete the assembly of the cam 66, the washers 102, and the springs 100.

It will be remembered that the sleeve 34 and the shaft 30, both being square, turn together, and are driven by the hand-wheel 14, subject to the control of a detent mechanism and of a delay mechanism, hereinbefore mentioned. The detent mechanism will now be described, still referring to Fig. 2. About the shaft 30 (but not about the sleeve 34) there is a star-wheel or cam 114 indexed to it by the chamfer 32 on the shaft, and having nodes 116 (see Fig. 5) between which there are valleys 118. Cooperating with this star-wheel 114, there are followers in the nature of the wedges 120, to ride from one valley 118 to another valley while passing over the nodes 116, under the control of springs 122 pressing against the followers 120. The outer ends of the springs are seated against seats 124 presented by a metallic lining 126 for a housing 128 of insulating material affixed to the rods 24. In this embodiment there are other springs 130 within the springs 122 to reinforce the latter. Thus, the described detent mechanism enforces upon the cam 66 a proper movement to impel and to impart to the moving contacts a proper or normal speed and hence to prevent, or at least to minimize, arcing, to reduce wear of the contacts, and to reduce heating.

The form of the track 68 of the cam 66 (see Fig. 6) is such that in normal operation the breaking of the circuit occurs within one-half of a cycle. The "break" occurs when the follower 120 is climbing from the valley 118 toward the top of the node 116. On the other hand,

the "make" occurs when the follower 120 is descending from the top of the node toward the valley. As a result, there is a slow "break" and there is a fast "make." This is a result greatly to be desired. One factor, and an important one, is the form of the cam-track (see Fig. 9A) in which it will be observed that the total movement takes place, in this instance, in angular distance 101.4°, while the remainder of the track is straight, as shown. That is, while the shaft is turning through 120° the bridge is reciprocated during substantially five-sixths of this period with equal periods of rest at the extremes of the period. Each bridge, it will be understood, is also at rest in raised position during two-thirds of the shaft revolution wherein the third of the cam including the rise is in the sector of the circle in which lie one or the other of the other two pairs of contacts. This form gives the desired breaking of the circuit within one-half of a cycle, at times much less than one-half cycle. Although the hand-wheel 14 may be turned in either direction, nevertheless, the desired slow "break" and the fast "make" can be achieved because of the fact that the "make" occurs when the follower 120 is descending from the top of the node toward the valley, whereas "break" occurs when the follower is ascending the rise from the valley.

Thus, the combination of the cam and the detent mechanism produces results hereinbefore described, namely, (1) the control of the rate of contact separation, so that a minimum amount of arcing occurs, because the current is permitted to break while the contacts are sufficiently close to effectively carry away the heat of the arc, and to partially exclude air which would otherwise carry oxygen to help maintain the arc, (2) positive indexing of the shaft, its associated cam, the contacts and the handwheel in the various "on" and "off" positions, so that the contacts may not be left in a partially opened or partially closed relation to each other.

The star wheel 114 and spring-pressed followers 120 impose substantial resistance to rotation of the shaft enforcing a slow initial movement resulting, when the movement is for 60° in the example shown from an "on" to an "off" position, in a slow "break." The resistance may be substantially the limit of a man's capacity. Thus he cannot dash on the way but must take the hill on the rush so to speak, thus ensuring that separating movement is fully effected. As the detents pass the crests of the star wheel teeth the stored energy in the springs is released so the detents then coast down the hill rapidly tending to drive the wheel and causing, when the shift is from an "off" to an "on" position, a quick "make." The effort required by the operator to surmount the hill is such that he cannot hold back during this action.

It might be possible however that after moving from an "on" position the impetus imparted to the shaft under continued forced exerted by the operator might carry it through the "off" position past the next tooth to a succeeding "on" position at such a short interval that undesirable results would ensue. Therefore the switch disclosed provides a detent mechanism to stop it at, or substantially at, an "off" position if the moving parts are then turning at such a speed as to make an overthrow as described possible. This detent mechanism will now be described, referring now to Figs. 2, 3 and 4. A plate 132

is affixed to the shaft 30, turns in housing disk 134 affixed to the rods 24 (see Fig. 3) and carries one or more, herein three disks 136 each having affixed to it flat springs 138 whose outer ends are anchored to the plate 132. Thus, each disk 136 can turn in the plate 132 and will return to its normal position under the influence of its springs 138. Ample space for the play of the springs is provided by slots 140 in the plate 132. Each disk 136 carries a follower, herein a ball 142 which can play to and fro within a slot 144 and its travel in one direction (outwardly) is assisted by a spring 146. This ball is thrust outwardly by the spring against the inner margin 143 of the housing 134, and this margin has one or more, herein three ramps, cams, or teeth 150, which project into the path of the ball. (See Fig. 3.) The inner end of the spring 146 has a rider 152 resting against a fixed plate 154.

The combination of the tooth angle and the forces of the springs 138 and the springs 146 is such that in the slow or normal operation of the switch, the ball 142 will ride over the tooth 150 without interference. However if the shaft 30 is moving at excessive speed the inertia of disks 136 and the parts carried thereby tending to cause them to move along the tangent is greatly increased (proportionately to the square of the velocity). When the ball strikes the obliquely presented side of tooth 150 the equal and opposite counterforce is correspondingly great and its component perpendicular to the slot 144 overcomes the resistance of springs 138, causing the disk to swing (counterclockwise viewing Fig. 2 if the shaft is turning clockwise) to a position wherein the slot is more or less parallel to the slope of the tooth, and the ball is caught between the side of the slot and the side of the tooth and locks them against further approximation. This locking action can be removed only by releasing rotational pressure of the hand-wheel 14 and the shaft 32 upon the driving plate 132. It will be apparent from comparison of Figs. 1 and 3 that the teeth 150 are in alignment with the "off" positions of the switch and the detents are so angularly related to the bridges that the detents come into apposition to the teeth as the bridges move to the "off" position. If the teeth were angularly spaced from the "off" positions the angular relation of the detents to the bridges would be similarly modified. Thus if the shaft is turning too rapidly as it comes to the "off" position it will be locked and its motion arrested without possibility of overthrow to the succeeding "on" position.

At the outset, the advantages, the objects, and the general functions were outlined fully, and it is deemed unnecessary to repeat them here, in view of the full description of the operation of each mechanism. It will suffice to say that the combination of the several mechanisms achieves important results never hereinbefore achieved in a switch, so far as I am aware.

Having described one embodiment of the invention, what I claim is:

1. A switch particularly adapted for the distribution of high potential alternating current which is organized within a restricted cylindrical volume and comprises an axial rotatable shaft having provision at one end for applying turning force thereto, a group of contacts ranged around the shaft radially remote from the same and presenting contact faces in the axial direction, a set of bridge pieces similarly ranged around

the shaft for movement in the axial direction to and from said faces, a cam of the axially operating type on the shaft within the axially projected area of the group of contacts, followers cooperating with the cam and connected to said bridges respectively providing for successive operation of the bridges on continued rotation of the shaft, a wheel on the shaft having lobes at its edge angularly coordinated with the contacts and spring loaded followers normally thrust inwardly toward said wheel and providing substantial resistance to the turning of the shaft as the followers climb a lobe contemporaneously with the action of the cam in separating a bridge from its contacts and provided for release of spring-stored energy when the followers have passed the crest of the lobe to facilitate further turning of the shaft as the cam is approximating a bridge and its contacts.

2. A switch as defined in claim 1 wherein the followers cooperating with the wheel are radial plungers supported by radially arranged compression springs.

3. A switch particularly adapted for the distribution of high potential alternating current which is organized within a restricted cylindrical volume and comprises an axial rotatable shaft having provision at one end for applying turning force thereto, a group of contacts ranged around the shaft radially remote from the same and presenting contact faces in the axial direction, a set of bridge pieces similarly ranged around the shaft for movement in the axial direction to and from said faces, a cam of the axially operating type on the shaft within the axially projected area of the group of contacts, followers cooperating with the cam and connected to said bridges respectively providing for successive operation of the bridges on continued rotation of the shaft, and an indexing mechanism cooperating with said shaft defining the closed positions of the several bridges and intermediate open positions.

4. A switch as defined in claim 3 wherein the contacts and the bridges are arranged in chambers in a body of insulating material closely fitting their lateral contours and having a wall extending across the plane of contact between them.

5. A switch as defined in claim 3 wherein the portions of the connections from the bridges to the cam followers which project from the latter and the cam are encircled by a sleeve of insulating material having channels the walls of which closely approximate those portions of the connecting elements not directly opposing the cam.

6. A switch comprising an axial rotatable shaft having provision for applying turning force thereto, pairs of contacts located in sectors of a circle about the shaft and radially remote from the shaft, bridges which connect the contacts by closing thereon in a generally axial direction, means for driving the bridges from the shaft to reciprocate the bridges to and from the pairs of contacts successively on rotation of the shaft through corresponding sectors, a lobed indexing wheel on the shaft having twice as many lobes as there are pairs of contacts to provide for indexing the bridge in "on" positions and intermediate "off" positions and a spring-pressed follower cooperating with said wheel to be displaced by the lobes when the shaft is started into movement.

7. A switch as defined in claim 6 wherein the driving means for the bridge reciprocates it during the major portion of the period of rotary

movement of the shaft between successive "on" positions of contacts with substantially equal periods of rest at the extremes of said period.

8. A switch as defined in claim 6 wherein there are three pairs of contacts and the driving means for the bridge reciprocates it during substantially five-sixths of each one-third turn of the shaft with substantially equal periods of rest at the extremes of said period.

10. 9. A switch comprising an axial rotatable operating shaft, pairs of contacts presenting contact faces in the axial direction located in sectors of the circle about the shaft, bridges, a driving mechanism connecting the shaft to the bridges effective on rotation of the former, through corresponding sectors to reciprocate the bridges successively to "on" positions bridging the several pairs of contacts, an indexing means yieldable to rotating pressure on the shaft for positioning it 20 in the several "on" and intermediate "off" positions and including an energy storing device in which energy derived from the shaft is charged during movement of the bridge from "on" position and which is released to the shaft during movement 25 of the bridge toward "on" position.

10. A switch comprising a rotatable operating shaft, pairs of contacts presenting contact faces in the axial direction located in sectors of the circle about the shaft, bridges for the pairs, a 30 driving mechanism connecting the shaft to the bridges effective on rotation of the former through corresponding sectors to give the bridges movements of axial reciprocation from "on" position bridging a pair of contacts, through an intermediate "off" position to an "on" position, an energy storing means organized in force transmitting relation with the shaft to receive energy therefrom during movement of a bridge from "on" position and to release such energy thereto during movement 40 of a bridge to "on" position and a locking mechanism for preventing rapid movement of the shaft through "off" position comprising a balanced detent revolving with the shaft and responsive to inertia on excessive speed of the shaft to move into locking position between the shaft and a fixed member, the angular relation of the fixed member to the "off" position of the bridge corresponding to the angular relation of the detent to the bridge itself.

50. 11. A switch particularly adapted for the distribution of high potential alternating current comprising a rotatable shaft having provision for applying turning force thereto, pairs of contacts ranged around the shaft radially remote from the same, bridge pieces for connecting the contacts of the several pairs connected to the shaft for movement thereby successively to "on" positions and through intermediate "off" positions on rotation of the shaft and delay means to prevent the bridge, if the shaft turns at excessive speed, from passing through an "off" position comprising a detent moving around with the shaft, a fixed tooth external to the detent, the two being angularly positioned to appose one another 60 substantially when the bridge comes to "off" position, the detent being spring balanced and normally moving freely over the tooth when the shaft turns slowly but yielding to inertia on excessive speed of the shaft to move into locking relation 65 to the tooth.

70. 12. A switch particularly adapted for the distribution of high potential alternating current comprising a rotatable shaft having provision for applying turning force thereto, pairs of contacts ranged around the shaft radially remote from the

same, bridge pieces for connecting the contacts of the several pairs connected to the shaft for movement thereby successively to "on" positions and through intermediate "off" positions on rotation of the shaft, an indexing disc on the shaft and spring-supported positioning device cooperating therewith to position the bridges in their several "on" and "off" positions, the cooperation of said parts resisting rotation of the shaft and effecting energy storage in the supporting spring as a bridge is moved from such a position and releasing such energy to the shaft as the bridge then moves to the next position and delay means to prevent the switch, if the shaft turns at excessive speed, from passing through an "off" position comprising a detent moving around with the shaft, a fixed tooth external to the detent, the two being angularly positioned to appose one another substantially when the bridge comes to "off" position, the detent being spring balanced and normally moving freely over the tooth when the shaft turns slowly but yieldingly to inertia on excessive speed of the shaft to move into locking relation to the tooth.

13. A switch particularly adapted for the distribution of high potential alternating current comprising a rotatable shaft having provision for applying turning force thereto, pairs of contacts ranged around the shaft radially remote from the same, bridge pieces for connecting the contacts of the several pairs connected to the shaft for movement thereby successively to "on" positions and through intermediate "off" positions on rotation of the shaft and means comprising a movable part revolving with and about said shaft and a fixed part angularly located to be in apposition to said part when the bridge comes to "off" position, the movable part being displace-

able by inertia on excessive speed of the shaft to effect a locking engagement with the fixed part.

14. In a switch, the combination of a rotary shaft, contacts which are separated or approximated on determined rotative movements of the shaft, a pair of contacts operated by said shaft, and delay mechanism to delay operation of said shaft in case of abnormal, rotational speed of the shaft, including a stationary tooth, a plate affixed to the shaft, a follower on the plate arranged normally to ride over said tooth, and means to prevent said follower from riding over said tooth at a speed greater than normal, said means including a disc arranged to turn about an axis on said plate, a spring to return said disc to a normal position with reference to said plate, said follower being carried by said disc, and a spring to thrust said follower toward said tooth, the combination of the tooth angle and the forces of said springs being such that normally said follower will ride over said tooth, but when too rapid rotation of the shaft occurs, the follower is prevented from ascending said tooth.

25 GEORGE E. BREEZE.
